FIG. 6

UNITED STATES PATENT OFFICE

ERNEST J. SCHUDA, OF ERIE, PENNSYLVANIA, ASSIGNOR TO LOVELL MANUFACTURING COMPANY, OF ERIE, PENNSYLVANIA, A CORPORATION OF PENNSYLVANIA

WRINGER

Application filed September 9, 1929. Serial No. 391,175.

The invention is particularly directed to an improvement in drip boards of wringers. These boards are commonly made with inclined surfaces toward both faces of the wringer and are provided with a tilting board at the center which reverses the flow of water from the wringer to either side so that the wringer may be used from either side. It is desirable to mount such tilting apparatus on the drip board and it is very often desirable to remove the tilting board in order that the drip board may be thoroughly cleaned, or repolished. It is also desirable to facilitate the assembly of the drip board and tilting board. In the present invention, the tilting board is made detachable. It is yieldingly locked in adjustment by a spring and the spring is utilized in maintaining the pivotal connection between the tilting board and the drip board, but yields to permit of the ready detachment of the tilting board when desired. Features and details of the invention will appear from the specification and claims.

A preferred embodiment of the invention is illustrated in the accompanying drawings as follows:

Fig. 1 shows a front elevation of the wringer.

Fig. 2 a section on the line 2—2 in Fig. 1.

Fig. 3 a similar section enlarged.

Fig. 4 a section on the line 4—4 in Fig. 2.

Fig. 5 a section similar to Fig. 3 showing the tilting board as it is being detached.

Fig. 6 a view showing the spring controlling the tilting board in elevation.

1 marks the wringer base, 2 the side stiles, 3 the top bar, 4 the lower roll and 5 the upper roll. These are, or may be, of any desired construction.

A drip board 6 has a flat central portion 7 which is secured to the base 1 by bolts 8. It is provided with the inclined drip directing plates 9 which extend from the central portion 7. Flanges 10 extend along each side of the drip plate. The upper edge of this flange is preferably folded over at 11.

A tilting plate 12 has the water-shedding plate 13 with side flanges 14. At the centers of the side flanges there are formed round-

ended projections 15, the upper edges of these projections forming cylindrical, or pivotal surfaces. The projection 15 is formed by notching the flange at each side of the projection at 16.

An inwardly projecting plate 17 having its under surface cylindrical forms a down-faced pivotal surface for receiving the pivotal surface of the projection 15. The plate 17 is formed on a clip 17a. The clip 17a has ears 18 at each side of the plate 17 which are folded down over the flange 10 of the drip board. A rivet 19 is passed through the clip 17a and the flange 10 at the lower end of the clip. This rivet is set up and the ears 18 closed in the same press operation, thus giving a rigid construction. It is preferable to form the plate 17 in a separate piece from the flange 10 in that it is comparatively small and any injury to it would result in the discarding of the entire drip board.

A spring 20 has a rounded end 21 which engages a projection 22 formed in the bottom of the tilting board. The spring is secured to the drip board by a rivet 23. This spring is an ordinary leaf spring, when released having a position somewhat above that shown in Fig. 6.

In the operation of the drip board, the spring yieldingly forces the pivotal surface of the projection 15 into rocking engagement with the plate 17. As the drip board is reversed, the projection 22 acts on the end of the spring and depresses it so that as the projection is carried by the center of the spring it snaps the tilting board into reverse position and yieldingly holds it in this adjustment. When it is desired to remove the tilting board all that is necessary is to depress the spring and this will permit of the downward movement of the projection 15 out of engagement with the projection 17. The tilting board may then be moved out from under the projection 17 and thus removed from the drip board. Thus this detachment can be made readily without any special tools and without in any way marring any of the parts of the drip board, or tilting board. This is of importance as these parts must be properly plated to prevent rust.

What I claim as new is:—

1. In a wringer, the combination of a tilting board support; a tilting board on the support; and a pivotal connection between the support and the tilting board, said connection including yieldable engaging parts manually operable to detach the tilting board. 70
2. In a wringer, the combination of a tilting board support; a tilting board on the support; a pivotal connection between the support and tilting board, said pivotal connection comprising inner and outer pivotal members, the outer pivotal member being open at one side permitting a cross movement of the inner member into pivotal engagement with the outer member; and a spring holding the connection in place, said connection being detachable through the yielding of the spring. 75
3. In a wringer, the combination of a tilting board support; a tilting board on the support; a pivotal connection between the support and the tilting board, said pivotal connection comprising inner and outer pivotal members, the outer pivotal member being open at one side permitting a cross movement of the inner member into pivotal engagement with the outer member; and a spring yieldingly holding the tilting board in adjustment. 80
4. In a wringer, the combination of a tilting board support; a tilting board on the support; a pivotal connection comprising a downwardly faced engaging surface on the support and an upwardly faced engaging surface on the tilting board; and a spring yieldingly holding the surfaces in engagement. 85
5. In a wringer, the combination of a tilting board support; a tilting board on the support; a pivotal connection having a downwardly faced engaging surface on the support and an upwardly faced engaging surface on the tilting board; a spring yieldingly holding the surfaces in engagement; and means engaged by the spring holding the tilting board in adjustment. 90
6. In a wringer, the combination of a drip board having side flanges with downwardly faced pivotal surfaces formed at the centers of said side flanges; a tilting board having flanges at its edges and upwardly faced pivotal surfaces formed on said flanges engaging the pivotal surfaces on the drip board; and means holding the upwardly faced tilting pivotal surfaces in engagement with the downwardly faced pivotal surfaces of the drip board. 95
7. In a wringer, the combination of a drip board having side flanges with downwardly faced pivotal surfaces on said side flanges; a tilting board comprising flanges at its edges and upwardly faced pivotal surfaces formed on said last mentioned flanges engaging the pivotal surfaces on the drip board; and a spring yieldingly holding said surfaces in engagement. 100
8. In a wringer, the combination of a drip board having side flanges with downwardly faced pivotal surfaces on said side flanges; a tilting board comprising flanges at its edges and upwardly faced pivotal surfaces 105 formed on said last-mentioned flanges engaging the pivotal surfaces on the drip board; a spring yieldingly holding said surfaces in engagement; and means engaged by the spring holding the tilting board in adjustment. 110
9. In a wringer, the combination of a drip board having side flanges; clips secured to the side flanges, said clips having inward projections with downwardly faced pivotal surfaces; a tilting board having flanges at its edges with upwardly faced pivotal surfaces, said pivotal surfaces engaging the pivotal surfaces on the drip board; and means holding the upwardly faced tilting pivotal surfaces in engagement with the downwardly faced pivotal surfaces of the drip board. 115

In testimony whereof I have hereunto set my hand.

ERNEST J. SCHUDA. 95
